UNITED STATES PATENT OFFICE.

WILLIAM C. DAVIS, JR., OF JASPER, ALABAMA.

SAFETY-SWITCH SYSTEM.

Application filed March 18, 1927. Serial No. 176,476.

This invention relates to a safety switch system, and particularly to a train control switch disposed in cooperative relation to the regular or normal switch for directing a train from one track to another, and adapted to supplement such regular switch in case of failure of the same to properly operate.

Many serious railway accidents have occurred by misplaced switches or where the speed of the train was such as to cause it to overrun the switch and fail to take the siding. This is particularly the case on single track railroads where it is customary for one train when reaching a siding to await the arrival of a second train which is intended to pass the first arriving train either on the main line or by siding.

A number of collisions between trains have recently occurred through failure of the regular switch to properly act, either by carelessness or by accident, and the present invention seeks to positively insure the switching action by use of a supplemental safety switch which is solely controlled by the first train arriving at the point of passing, so that if the later arriving train fails to keep its proper track it will be directed thereto by a cross-over section extending between the main line and the siding.

The operation of such a safety switch is preferably electrically controlled by a third rail and a contact device carried by the train and such a switch includes a switch releasing device disposed at a point remote from the position where the first arriving train is standing.

The invention has for an object to provide a construction of safety switch adapted to cooperate with separate tracks and the normal switch connecting the same, such safety switch being directly controlled by the first arriving train to prevent a subsequent arriving train from entering the same section of track.

A further object of the invention is to provide a system in which both the main line and siding are provided with third rail power conveyors in circuit with safety switches which control cross-over sections extending between the main line and siding, such switches being operable by a contact device establishing circuit between the third rail and the track rails.

A further object of the invention is to provide a system embodying separate tracks with

a normal switch connection between the same and independent cross-over connections from one track to the other, such cross-overs being controlled by an electric switch adapted to be released by a circuit established by a train control device and to be restored in the subsequent passage of a train in a direction opposite to the other end of the switch point.

Other objects and advantages of the invention will be hereinafter set forth and the novel features thereof defined by the appended claims.

In the accompanying drawing:—

Figure 1 is a diagram showing the track arrangement with the electric connections;

Figure 2 is an enlarged plan of the left portion of Figure 1;

Figure 3 is a detail plan of one of the safety switches;

Figure 4 is a detail perspective of the switch point and its retaining device; and

Figure 5 is an elevation of the contact device carried by a train.

Like reference characters designate corresponding parts throughout the several figures of the drawing.

The invention is adapted for various applications and in different positions relative to the separate tracks to be controlled, and for the purpose of illustration is herein shown as having the safety switches controlling both ends of a siding.

As shown in Figure 1, the main line track 10 is associated with a second or siding track 11 and these are connected at opposite ends of the main section of the track 10 by means of cross-over tracks 12 which are solely train-controlled. At the connection of the siding 11 with the main line 10 normal or regular switches 13 and 14 are provided. The cross-over track 12 first mentioned is intersected by an oppositely disposed cross-over track 15 and the tracks 12 and 15 are provided with the usual spring switches at 16 at their outlets adapted to be opened by the wheel flange of a passing train and automatically closed.

Cooperating with the trackage system just described is a series of third rail sections disposed in associated relation with the main line and siding tracks. The separated sections 17 and 18 are located on the main line, and similar sections 19 and 20 disposed between the rails of the siding. From the third rail section 17 a circuit 21 extends to an electrically operated switch 22 associated with the cross-

over 15 at its juncture with the main line. The rail section 18 is provided with a circuit 23 extending to a safety switch 24 for its electrical control. The third rail 19 of the siding has a circuit 25 extending to the switch 26 controlling the entrance into the cross-over 12 while the third rail section 20 of the siding has circuit connection at 27 with the safety switch 28 controlling the entrance into the cross-over 12 at its end next the main line.

The return circuit from the several electric switches described may be through a line 29 extending to a power line 30, while the opposite power line 31 is electrically connected at 32 with the main line track rails. It is understood that these various electrical connections are suitably insulated and protected at their points of intersection or crossing the track rails.

Any desired form of electrically controlled switch may be used in connection with the invention but a preferred construction thereof is shown in Figures 3 and 4 and forms the subject of an application filed of even date herewith. In this form of the invention the switch frog or point 35 is thrown in open position by a tension spring 36 but is usually held in closed position against the tension of such spring by a latch 37 which passes through an aperture 38 in the switch point 35 and engages the rear wall thereof. This latch is impelled toward a retaining position by a spring 39 extending therefrom to a fixed point and the latch suitably pivoted at 39 upon any desired support. This latch is provided with an armature member 40 which is adapted to be attracted by an electro-magnet 41 from which the circuit connections 42 extend. This magnet when energized swings the latch out of engagement with the switch point and against the tension of the spring 39 so that the switch is opened by the action of the spring 36 and remains in that position until the passage of a wheel upon the rail in a direction away from the switch pivot forces the point toward the associated rail where it is automatically latched by the action of the spring 39 as at that time the magnet is not energized.

For the purpose of establishing circuit between the third rail and track rails to energize the switch magnet, various devices might be used, a simple form of which comprises the shoe 43 mounted upon the train, for instance the locomotive, and having a supporting rod 44 extending to an operating lever 45 which is normally held in raised position by a spring 46 extending therefrom to a support 47. As indicated in Figure 5, the circuit is carried from the third rail through a suitable support 48 to the train wheels which establish the return circuit by the line 32 to the source of power.

The action of the switch is automatic after its release by the train device, and the parts

described may be suitably protected by a casing of any preferred form.

The invention is adapted for a number of different applications, several of which will be referred to in explaining the operation.

Assume that the first arriving train passes the closed switch 13 at the left of Figure 1 and remains on the main line in position for the operator to establish circuit through the third rail 17 which releases and opens the safety switch at 22. Under this condition, if a train approaches from the right and fails to take the switch at 14 onto the siding 11, it would continue on the main line until it reached the safety switch and would be there directed into the cross-over 15 onto the siding section. If the train first arriving is to await a passing train upon the siding section and approaches from the left of Figure 1, it will take the switch at 13 entering the siding and make circuit through the third rail 19 so as to energize the safety switch 26 through the line 25. If for any reason a train approaching from the right does not continue on the main line but enters the siding, it will be safely directed by the switch 26 onto the cross-over 12.

From the circuit connections shown in Figure 1, it will be seen that a similar operation to that just described will occur if the first train arriving at the point of passing is travelling in a direction toward the right of said figure, as the third rail section 18 of the main line controls the switch 24 and the similar section 20 of the siding controls the switch 28.

From the foregoing description it will be seen that the invention presents a simple and efficient safety switch adapted to be controlled by a train first arriving at a siding so as to effectually prevent accident by collision with a train approaching from an opposite direction and entering the section of track upon which the standing train is disposed.

While the details of the invention have been specifically shown and described with their various circuit connections, the invention is not confined thereto as changes and alterations may be made without departing from the spirit thereof as defined by the following claims.

Having thus described my invention, what I claim as new and desire to secure by Letters Patent of the United States, is:

1. In a safety switch system, the combination with separate tracks and a normal switch connecting the same, oppositely disposed cross-over tracks extending between the separate tracks, and train controlled switches at the entrance to each of said cross-over tracks.
2. In a safety switch system, the combination with separate tracks and a normal switch connecting the same, oppositely disposed cross-over tracks extending between the separate tracks, train controlled switches at the

entrance to each of said cross-over tracks, third rail power sections associated with each of the tracks, and circuit connections therefrom to control the safety switch at a point 5 removed from the third rail section contacted by the train device.

3. In a safety switch system, a main line track, a siding track having switch connection therewith at opposite ends, cross-overs 10 between the siding and main track, safety switches controlling the entrance to said cross-overs, and train controlled means for actuating one of the safety switches from the train first arriving at the point of meeting. 15 4. In a safety switch system, a main line track, a siding track having switch connections therewith at opposite ends, cross-over tracks extending between the siding and main line tracks adjacent said switch connections, 20 a power third rail associated with both the main line and siding tracks, electrically controlled switches at one end of each of said cross-overs, and circuit connections between the third rails and said switches to the track 25 rails.

5. In a safety switch system, a main line track, a siding track having switch connections therewith at opposite ends, cross-over tracks extending between the siding and main 30 line tracks adjacent said switch connections, a power third rail associated with both the main line and siding tracks, electrically controlled switches at one end of each of said cross-overs, and circuit connections between 35 the third rails and said switches to the track rails, the third rail at one end of the track

sections being disposed to control the electric switch at the opposite end thereof.

6. In a safety switch system, a main line track, a switch track, a switch member controlling the entrance to said switch track, means for normally holding said switch member in position for main line travel, a third rail adapted to be engaged by a train carried device, and circuit connections from said third rail for releasing said switch member after passage of a train on the main line to automatically establish switch track connections and prevent a following train entering the main line track. 40 45 50

7. In a safety switch system, a main line track, a switch track, a switch member controlling the entrance to said switch track, means for normally holding said switch for main line travel, and train controlled means for automatically establishing switch track connection after the passage of a train upon the main line track over said switch. 55

8. In a safety switch system, a main line track, a switch track, a switch member controlling the entrance to said switch, means for normally holding said switch for main line travel, train controlled means for automatically establishing switch track connection after the passage of a train upon the main line track over said switch, and means for automatically retaining said switch in main line position actuated by the passage of a train over the switch member in an opposite direction. 60 65 70

In testimony whereof I affix my signature.
WILLIAM C. DAVIS, JR.
